(57) **CLAIM**

The ornamental design for printed circuit board for electrical connector, as shown and described.

DESCRIPTION

FIG. 1 is a view of one face of the printed circuit board for electrical connector;

FIG. 2 is a side view of the printed circuit board for electrical connector;

FIG. 3 is a view of an opposite face of the printed circuit board for electrical connector to the face shown in FIG. 1; and,

FIG. 4 is a perspective view of the printed circuit board for electrical connector.
